DESIGN FOR A TUCKED FABRIC

Michael B. Kaplan, New York, N. Y.

Application June 15, 1940, Serial No. 93,032

Term of patent 3½ years

To all whom it may concern:

Be it known that I, Michael B. Kaplan, a citizen of the United States of America, residing in New York city, in the Borough of Manhattan, county and State of New York, have invented a new, original, and ornamental Design for a Tucked Fabric, of which the following is a specification, reference being had to the accompanying drawing, forming part thereof, wherein the figure is a plan view of a piece of tucked fabric showing my new design.

I claim:

The ornamental design for a tucked fabric, substantially as shown.

MICHAEL B. KAPLAN.
